UNITED STATES PATENT OFFICE.

WILLIAM H. BAKER, OF CENTRAL FALLS, RHODE ISLAND, AND FREDERIC E. KIP, OF MONTCLAIR, NEW JERSEY.

LOOM.

SPECIFICATION forming part of Letters Patent No. 637,195, dated November 14, 1899.

Application filed June 26, 1899. Serial No. 721,802. (No model.)

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented certain new and useful Improvements in Looms, of which the following is a specification.

- 10 This invention relates to that class of looms wherein weft or filling is supplied automatically as it is taken up in the weaving and the weft-supplying mechanism belongs to the class in which filled shuttles or weft-holders are supplied as needed from a suitable magazine, electricity being employed, by preference, to announce the exhaustion of the weft in the active shuttle or shuttle in play and to control the operation of the supply.
- 20 In the loom of this application the shuttles are placed in a magazine, and a double, two-celled, or compound shuttle-box is employed, this latter being adapted to be shifted to take a fresh shuttle from the magazine into its working cell while the exhausted shuttle (in play) is in the shuttle-box at the opposite side of the loom and to put the auxiliary cell of the compound shuttle-box into line for the time with the shuttle-race, so that it may receive the exhausted shuttle when shot back from the opposite side. When the compound box shifts to bring the fresh shuttle into play, the auxiliary cell is opened to permit the exhausted shuttle to be thrown out as the lay
- 30 or batten recedes, said shuttle falling into a suitable receptacle on the loom.

One important feature of the invention consists in providing the shuttle-box at the opposite side of the loom from the magazine with controlling devices, as the electrical circuit-closing contacts, whereby the operating and controlling circuit employed herein is closed while the exhausted shuttle is out of the compound shifting box, thus permitting the latter to be shifted at the next beating-up stroke of the lay and also permitting the exhausted shuttle to enter the auxiliary cell on the return shot.

Another important feature of the invention resides in the weft-holder in the shuttle, wherein the partial denudation of the weft

or filling completes the operating-circuit, all of which will be fully described hereinafter and its novel features defined in the claims.

In the accompanying drawings, which serve 55 to illustrate an embodiment of the invention, Figure 1 is a sectional elevation of that side and part of a loom where the weft-supplying mechanism is situated and showing the compound shuttle-box depressed or in its normal 60 working position, and Fig. 2 is a similar view showing the compound box elevated and taking in a fresh shuttle from the magazine. The plane of the section is at x' in Fig. 3. Fig. 3 is an elevation of the parts shown in 65 Figs. 1 and 2, the view being from the left in Fig. 1. These views show in full lines the lay or batten in its beating-up position. Fig. 4 is a horizontal section at line x^4 in Figs. 1 and 3. Fig. 5 is an enlarged perspective 70 view of the cam-plate C. Fig. 6 is a perspective view of the compound shuttle-box B detached. Fig. 7 is an end view of the magazine, showing the means for rotating the drum therein. Fig. 8 is a side elevation of 75 the non-shifting shuttle-box at the opposite side of the loom from the magazine. This view shows the circuit terminals. Fig. 9 is a vertical longitudinal mid-section of the shuttle, and Fig. 10 is a plan view of the shuttle. 80 Fig. 11 is a view of the cop detached. Figs. 8 to 11 are drawn to a scale double that of the principal views. Figs. 12, 13, 14, 15, and 16 are fragmentary detail views that will be 85 fully described hereinafter.

Let F represent the loom-frame; L, the lay; M, the magazine as a whole; S, the fresh or filled shuttles; S^x , an exhausted shuttle; B, the compound or two-celled shifting shuttle-box as a whole; B^x , the non-shifting shuttle-box, (seen in Figs. 8 and 10;) P, the picker-stick, and p the picker operating in connection with the shifting shuttle-box.

The magazine M, as shown in the principal views, is mounted on the loom-frame, and it 95 may be supported by brackets l on the breast-beam b of said frame. This magazine as preferably constructed comprises a shaft 2, having on it a rotatable drum 3, provided with cells 3^x for the filled shuttles S, said drum being inclosed in a fixed cylindrical casing 4, which keeps the shuttles from falling out of 100

the holders 3^x. This casing has at its under side a shuttle-pocket 5, into which falls the shuttle from the lowest cell of the drum 3 and from which the fresh shuttle is taken by 5 the shifting shuttle-box B. This pocket 5 occupies a position directly over and above the box B when the lay L is in its beating-up position (seen in Fig. 1) and is open at the side facing the lay. The drum 3, carrying the 10 shuttles, rotates intermittently, being actuated at proper times by the receding movement of the lay, and at each movement it brings a cell 3^x over the pocket 5, so that the shuttle may fall from the cell into the pocket.

15 The construction of the compound shuttle-box B and of the shifting mechanism for elevating and depressing it will now be described.

The box B consists of an upper or working 20 cell 6 and a lower auxiliary cell 6^x. These cells are best seen in the detached view, Fig. 6. The box B is guided in its vertical shifting movements in a bracket-frame 7 on the lay L and is fixed on the upper extremity of 25 a stem 8, which latter has a sliding bearing in a bracket 9, fixed on and moving with the lay. There will be, by preference, a spring 10 on the stem 8, which tends to draw down or depress the box B and assist gravity in this 30 respect; but the weight of the parts may be relied on to effect the depression.

To elevate the box B at the proper times and during the advancing movements of the lay and to support it in its elevated position during 35 the next receding movement of the lay, any suitable means may be employed. That herein shown will now be described.

On the loom-frame F at the proper point is mounted and fixed a cam-plate C, and on the 40 stem 8 is mounted an electromagnet 11, having its armature 12 mounted on the horizontal arm of an L-shaped armature-lever 13, the pendent arm 14 of which carries a stud or roller 15. Normally in the ordinary operation 45 of the loom the compound box B is depressed, the upper box or cell 6 thereof is alined with the race, and the end of the roller 15 plays as the lay vibrates near to but not in contact with the face of the fixed cam-plate C; but 50 when the electromagnet 11 is excited by the completion of the operating-circuit in a manner to be hereinafter described the armature 12 will be attracted and the lever thereof rocked, so that on the forward or beating-up 55 stroke of the lay the roller 15 will be projected so as to engage the inclined camway c, Fig. 5, on the plate C and will be caused to ride or roll up said inclined way, thus elevating the compound box B. After rising 60 the roller 15 will roll along and be upheld by the horizontal trackway c^x on the plate C. The upper cell 6 of the box B will now be in the same horizontal plane as the pocket 5 of the magazine, and when in its final position, 65 Fig. 2, the bottom of this cell 6 moves in under the shuttle S in the pocket, while two hooked spring-fingers 16 on the top of the box

B move in and wipe over the said shuttle, engaging it sufficiently to draw the shuttle laterally from the pocket 5 when the lay recedes. 70 During this receding movement of the lay the roller 15 travels back along the trackway c^x until the lay nears the end of its receding movement, when said roller drops off from a slight cam-shoulder c' onto a continuation c² 75 of the track c^x. At the end of the receding movement of the lay the exhausted shuttle S^x in the opposite shuttle-box B^x is shot across into the lower cell 6^x of the box B. The lay now advances again, and when the 80 roller 15 impinges on the cam-shoulder c' it rides off the trackway and the shuttle-box B falls or is depressed.

It may be explained here that in order to insure the roller 15 being held in place on the 85 camway and trackways of the plate C said roller is coned, as seen in Fig. 3, being largest at its outer end, and the camway and trackways are beveled, as clearly shown in the several views, so as to cause the roller to 90 hook over and keep its place, and it may also be stated that when the exhausted shuttle S^x leaves the box B^x the operating-circuit will be broken, so that when the inclined cam-shoulder c' rides or cams the roller 15 off from 95 the trackway c² said roller will clear the cam-plate C, as at first.

Mounted on the bracket 7, in which the box B is guided, is a spring-swell 17, such as is commonly employed on shuttle-boxes. This 100 swell is so situated on the bracket 7 that it comes into play with that cell in the box which is alined with the shuttle-race, or, in other words, it is so placed as to act in connection with the upper or working cell 6 normally; but when the box B is elevated it operates in connection with the auxiliary cell 6^x. Thus when the working cell is taking a 105 shuttle from the magazine, as in Fig. 2, the swell will be below, leaving that side of the upper cell 6 open, and when the box B is depressed the side of the cell 6^x will be left open, so that on the next receding movement of the lay the exhausted shuttle may be discarded 110 and thrown out from this cell into any suitable receptacle 18 on the loom-frame. It should be understood that the swell 17 and the picker p do not shift or move up and down with the box B, but only move to and fro with the lay. The bottom 6^b of the cell 6 of the box B may be made wavy or toothed, as indicated in Fig. 6, and the bottom of the pocket 5 correspondingly cut to match, so that when 115 said cell and pocket close together, as in Fig. 2, there may be no collision of the parts. 120

The drum 3 of the magazine M is rotated by the receding movement of the lay L after a fresh shuttle S has been taken into the working cell 6 of the elevated box B and rotated to an extent sufficient to bring the next cell 3^x into coincidence with the pocket 5, so that the shuttle in said cell may drop into the now empty pocket. The means for effecting this 125 partial and intermittent rotation of the drum

3 will now be described with especial reference to Figs. 1, 2, and 7. As herein shown, the drum 3 contains twelve cells 3^x , and it is intermittently rotated one-twelfth of a revolution at each impulse. On the end of the drum are twelve equally-spaced pins or studs 19, and on the box B is a spring-tappet 20, which normally or when the box is depressed plays under the lower stud of the concentric series; but when the box B is elevated on the advancing or beating-up stroke of the lay this tappet 20 strikes the said lower pin or stud on the drum, then yields and wipes past it by a well-known construction, and finally takes in front of it. When the lay next recedes, the tappet turns the drum by engagement with the pin to the desired extent and finally passes said pin. To steady the drum and determine its extent of rotation, a device is employed which may be seen at the left in Fig. 3. This device consists of a disk 21, with twelve radial V-shaped teeth fixed on the rotating drum, and a matching disk 21^x , held up in yielding engagement with the disk 21 by a spring 21^a , the disk 21^x being held against rotation, as by a guide-rod 21^b , in the bracket, on which rod said disk slides when it yields.

Referring now particularly to Figs. 8 to 11, the electrical controlling devices which we prefer will be described. Fig. 8 shows in side elevation the shuttle-box B^x at the opposite side of the loom from the box B. This box B^x may, for the purposes of our invention, be of any known kind. S^x represents, for example, an exhausted shuttle in said box in Fig. 8. On the box B^x are two spring-terminals t and t^x of an outer electric circuit or partial circuit $w w^x$, including a generator C and the coils of the electromagnet 11. When a shuttle is in the box B^x , the spring-terminals on the box are adapted to be put into electrical contact, respectively, with metal plates m and m^x on the shuttle, these latter forming terminals of an electric circuit or partial circuit within the shuttle, thus closing the two partial circuits into one. Figs. 9 and 10 show the construction within the shuttle. In the shuttle is hinged a spindle 22, which may be of metal, and on this spindle is slipped a cop 23, composed wholly of weft and known as an "all" cop. It may properly be explained here that in forming an all cop the weft thread or filling is wound on a smooth spindle, and when complete the cop or mass of weft is slipped off the spindle. The latter leaves a clear hole or bore in the cop, and when it is to be placed in the shuttle the weaver simply slips it onto the spindle therein, as indicated in Figs. 9 and 10. Fig. 11 shows the all cop detached. The spindle 22 is hollow at its butt and has fitted in it a tube 24, of insulating material, slotted at its inner end coincident with a slot or aperture in the wall of the spindle. Within the tube 24 is a metal terminal spring 25, which has a bend that tends to project out through the aperture in the spindle 22, and thus al-

low the free end of the terminal 25 to come into contact with the metal spindle. When the cop 23 is slipped onto the spindle, as in Fig. 9, the bend in the terminal 25 projects through a slot in the spindle and bears on the overwrapped weft covering the whole or a part of said slot or aperture, whereby said overwrapped weft maintains or holds the terminal 25 out of metallic contact with the spindle 22. The terminal 25 is connected electrically by a suitable conductor 26 with the terminal plate m on the shuttle, and the spindle 22 is similarly connected by a suitable conductor 26^x with the plate m^x . Thus it will be seen that normally with a full cop the weft will maintain a break in the partial circuit in the shuttle; but if the weft be exhausted to an extent sufficient to permit the terminal 25 to spring outward into contact with the metal spindle or with metal on the spindle, if the latter be not itself of metal, the circuit will be closed in the shuttle. Under these circumstances when such an exhausted shuttle enters the shuttle-box B^x the contact of the terminals t and t^x with the plates m and m^x will complete the circuit through the magnet 11.

Respecting the magazine M, it may be said that the size of the drum 3 is only limited by practicability of construction. The cells 3^x are filled, primarily, at a gate or door at 4^x in the casing 4. This gate may be at any point. In Figs. 1 and 2 (where part of the magazine is broken away) it appears at the side and in Fig. 7 it is at the top. There is a slide or slides 4^a to interpose between the drum and the pocket 5 temporarily while filling the cells 3^x , and the drum is rotated intermittently by hand to bring the cells consecutively to the filling opening or door. The dotted lines in Fig. 2 show the lay in its receded position. It is not essential nor desirable that the casing 4 shall wholly cover the cells 3^x . It may be sufficiently open to enable the weaver to note whether all of the cells 3^x are full or not. The purpose of this casing is merely to keep the shuttles from being thrown out of the cells in the drum 3. Any suitable provision may be made for filling the cells in the drum with filled shuttles.

Where the spindle 22 in the shuttle is not of metal, a metal contact-piece 22^a may be set therein, as represented in the fragmentary sectional view, Fig. 12, which shows the spindle denuded of weft.

Fig. 13 shows a slightly-modified form of the spring registering device seen at the left in Fig. 3 for holding the drum 3 against too easy rotation. In this construction a spring-finger 21^c , fixed on the bracket 1, engages the teeth of the disk 21 on the drum, said finger having an aperture to permit the passage of the journal of the drum. A thumb-piece 21^d on the finger enables the latter to be pressed back, so as to leave the drum 3 free to rotate.

Fig. 14 illustrates a slight variation of the

device for intermittently rotating the drum 3. This consists simply of a horizontally-arranged spring-latch 20^x, mounted on the compound shuttle-box and adapted to wipe under 5 the stud 19. It disengages in the same manner as the device 20. (Seen in Fig. 7.)

It is preferred that the bottom 5^x of the pocket 5, which may be any suitable shelf-like or finger-like support for the shuttle, 10 shall be tilted up slightly at its front or free edge, as shown in the enlarged fragmentary view, Fig. 15, so as to better retain the shuttle in the pocket, and to tilt the shuttle a little in order that the bottom 6^b of the cell 6 15 may conveniently take under the shuttle when the latter is being taken from the pocket 5.

Fig. 16 is a detail sectional view on a relatively large scale of the swell 17, showing 20 how it is beveled at 17^x, so as to permit it to pass over the side of the shuttle freely and keep the latter free from the hooked extremities of the spring-fingers 16. This view shows the relative positions of the parts.

25 The inclined trackway c, Fig. 5, will be, by preference, rounded or eased off at the top into the trackway c^x, so as to avoid the too abrupt passage of the roller 15, and the rod or stem 8 should have on it a stop-collar 8^a 30 or the like to prevent the box B from rising above a predetermined height.

Being the first in this field of invention, as we believe, and the first to employ a construction wherein a compound shuttle-box, as B, 35 is employed at one side of a loom, the movement of which is controlled by an electric operating-circuit, and wherein the circuit connections, closed by the exhausted shuttle, are situated at the shuttle-box on the side 40 opposite to said compound or cellular box, we do not limit ourselves to any specific devices or means for carrying out the object of the invention. For example, the well-known upright magazine may be employed with good 45 results, and other elevating and supporting devices for the box B might also be employed—as, for example, one of those shown in our pending applications, Serial No. 723,128, filed July 8, 1899, and Serial No. 724,385, filed 50 July 19, 1899.

An important feature of our invention is the circuit-closer situated within the ordinary spindle of a shuttle. This enables us to employ weft wound in the form of a cop, which 55 is adapted to be slipped directly on the spindle in the shuttle.

This construction is not limited to the particular weft-supplying mechanism herein shown, being as well adapted to controlling 60 the times of operation of other weft-supplying mechanisms.

Having thus described our invention, we claim—

1. A weft-supplying mechanism for looms, 65 having an elevatable, cellular or compound shuttle-box at one side of the loom, means for elevating said box, a shuttle-magazine, and

electrical controlling means at the shuttle-box on the opposite side of the loom set in operation by the presence of the exhausted shuttle in the last-mentioned shuttle-box for effecting the supply of a filled weft-holder to the shifting box from the magazine, and the discarding of the exhausted shuttle. 70

2. An electrically - controlled weft-supply mechanism for looms, having a shuttle-magazine, a shiftable, cellular or compound shuttle-box at one side of the loom, means for elevating said box to take in a shuttle from the shuttle-magazine, an operating - circuit, 80 and circuit-closing devices at the shuttle-box on the opposite side of the loom, set in operation by the presence of the exhausted shuttle in the last-mentioned shuttle-box, whereby the operating-circuit is closed and the box 85 elevated while the exhausted shuttle is on the opposite side of the loom from the magazine.

3. In a loom, the combination with a shiftable cellular shuttle-box and a magazine, at one side of the loom, means for elevating said 90 box in order to take a fresh shuttle into its working cell and to bring the auxiliary cell into line with the race, means for supporting said elevated box until the exhausted shuttle enters its lower cell from the opposite side, 95 and electrical means situated at the shuttle-box on the side of the loom opposite to the magazine, set in operation by the presence of the exhausted shuttle in the last-mentioned shuttle-box, for controlling the elevating of 100 the compound shuttle-box, whereby said shift is effected while the exhausted shuttle is out of the shifting shuttle-box.

4. In a loom, the combination with a shiftable, cellular shuttle-box on the lay at one 105 side of the loom and a weft-supply magazine at the same side of the loom with said box, of means for elevating said box so as to take a filled shuttle from the magazine into its working cell and at the same time bring its 110 auxiliary cell into line with the race, an operating electric circuit for controlling the elevating of the said shuttle-box, and closing devices for said circuit, situated at the shuttle-box on the side of the loom opposite to the 115 magazine and set in operation by the presence of the exhausted shuttle in the last-mentioned shuttle-box.

5. In a loom, the combination with a shiftable, cellular shuttle-box carried by the lay, 120 a magazine, and means for raising and lowering said box to an extent sufficient to bring the cells thereof alternately into line with the picker, of an electric circuit controlling said raising and lowering means, said circuit having closing devices at the shuttle-box on the side of the loom opposite to the magazine, which are set in operation by the presence of the exhausted shuttle in the last-mentioned shuttle-box, substantially as and for the purposes set forth. 125

6. In a loom, the combination with a shuttle-magazine on the loom-frame, the vibrating lay, a cellular, shiftable shuttle-box on the

lay on the same side of the loom with the magazine, means for elevating said box to take a shuttle from the lower pocket of the magazine, an electric circuit controlling said means and having in it a break at the shuttle-box opposite to the magazine, and the shuttle, having means for closing its partial circuit with the outer, operating-circuit, when it enters the last-mentioned shuttle-box and also having a circuit-closer held open by the overwrapped weft in the shuttle.

7. In a loom having automatic weft-supplying mechanism, the magazine M, having a pocket 5, at its lower part, and the drum 3, having shuttle-cells 3^x, in combination with the vibrating lay, the shifting shuttle-box thereon adapted when elevated to take a shuttle from said pocket, and means substantially as described for imparting intermittent rotation to the drum of said magazine.

8. In a loom, the combination with the vibrating lay, of a compound shuttle-box B, mounted to slide up and down in a guide thereon, the said guide, the picker, the swell 25 17, carried by the lay and adapted to close that cell of the box which is alined with the picker, means for elevating and supporting the box B when an exhausted shuttle enters the opposite shuttle-box on the lay and thereby actuates said means, means for depressing said box after the exhausted shuttle shall have entered the lower cell thereof, and a magazine to supply filled weft-carriers to the upper cell of the box B, substantially as set forth.

35 9. The combination with the lay, and the shifting shuttle-box carried thereon, of the means for elevating said box, comprising the magnet carried with said box, its armature 40 and armature-lever, the stud on said lever, the fixed cam-plate having camways adapted to be engaged by said stud when the magnet is excited, and means for exciting said magnet when the weft carried by the shuttle is 45 substantially exhausted.

10. In a loom, the combination with a shift-50 able, cellular shuttle-box, and a shuttle-magazine, of means for shifting said box in order to take a fresh shuttle into its working cell, 55 and to bring the auxiliary cell into line with the race, and means for controlling the time of the operation, said means comprising an open electric circuit including an electromagnet, and having in it a self-closing break consisting of two terminals situated within a hollow or cavity in the spindle of the shuttle, and which are held apart by the weft.

11. A shuttle having in it a partial electric circuit with terminals exterior to the shuttle, 60 and having in it a spindle provided with circuit-closing devices situated so as to be within the weft carried by the spindle.

12. A shuttle having in it a partial electric circuit, and having in it a spindle provided 65 with a hollow or recess, said hollow or recess containing an automatic circuit-closing device consisting of two terminals, both contact-

surfaces of which are situated wholly within the said hollow or recess in the spindle.

13. In a loom, the combination with the vibrating lay, and a magazine on the loom-frame having a shuttle-pocket at its bottom, of the shifting, cellular shuttle-box on the lay, said box being open at the side next the magazine for facility in receiving and discharging shuttles, and a swell carried by the lay and stationary with respect to the shuttle-box, said swell being adapted to close the open front of the cell in said box which is alined with the race, substantially as set forth.

14. A weft-supplying mechanism for looms, having a rotary magazine provided with shuttle-cells, and a stationary shuttle-pocket 5, below said magazine, which pocket is open at 85 the side toward the lay of the loom, substantially as set forth.

15. A weft-supplying mechanism for looms, having a rotatively mounted shuttle-magazine, means for imparting intermittent rotation thereto, and a stationary casing about said magazine, having a shuttle-pocket which is also stationary below the magazine, and open at the side toward the lay of the loom, substantially as set forth.

16. A weft-supplying mechanism for looms, having a rotary magazine, and a stationary shuttle-pocket 5 below said magazine, said pocket having its side toward the lay of the loom open, and having its bottom 5^x elevated 100 at its free edge, substantially as and for the purposes set forth.

17. The combination with a shuttle-box of a loom, having its bottom cut away in part, of a rotary shuttle-magazine, having a stationary pocket 5, open at the side toward the shuttle-box, the bottom of said pocket being cut away so that its parts intermesh with those of the bottom of the shuttle-box when the two are brought together, substantially as set forth.

18. A weft-supplying mechanism for looms, having a cam-plate C, provided with the inclined trackway c, merging at its upper end into the broader trackway c^x, the laterally-inclined shoulder c', and the continuing trackway c², and having also a roller, carried to and fro with the lay, to roll on said trackways, substantially as set forth.

19. A weft-supplying mechanism for looms, having a coned roller, 15, carried to and fro with the vibrating lay, and a cam-plate C, having trackways for said roller to roll along, said trackways being beveled as described, to retain said roller in place, substantially as set forth.

20. In a loom, the combination with the vibrating lay, of a shuttle-magazine, a shifting, cellular shuttle-box on the lay, mechanism for shifting said shuttle-box at proper times 130 to take in a shuttle from the magazine, and an open electric circuit controlling the operation of the shuttle-shifting mechanism, said circuit including an electromagnet and

having in it a break, the closure of which is controlled by the weft in the shuttle.

21. Weft-supply mechanism, comprising mechanism for supplying filled weft-carriers as required to a loom, of an electric circuit and mechanism controlling said supply mechanism, said circuit including a generator and having a break which is closed by the entry of a shuttle into the shuttle-box, and the 5 shuttles, each having in it an electric circuit which closes with the exterior circuit when the shuttle is in place in the shuttle-box, said shuttle having in it a spindle provided with a circuit-closing device situated so as to be 10 within the weft carried by the spindle.

22. In a loom having a weft-supply mechanism, the combination with mechanism for supplying filled weft-carriers as required to a loom, of an electric circuit and mechanism 20 controlling said supply mechanism, said circuit including a generator, a magnet, and a shuttle having in it a partial electric circuit, and having in it also a spindle provided with a hollow or recess, said hollow or recess containing an automatic circuit-closing device 25 consisting of two terminals both contact-surfaces of which are situated wholly within said hollow or recess in the spindle.

23. In a loom having a weft-supply mechanism, the combination with said weft-supply mechanism, of means for controlling the time of its operation, comprising an electrically-actuated device having its circuit extending through the shuttle and having a circuit maker and breaker attached to the spindle of the shuttle and so situated as to be 30 within the weft carried by said spindle, and the said spindle.

24. In a loom having a weft-supply mechanism, the combination with said weft-supply mechanism and means for controlling the time of its operation, said means consisting of a generator and magnet connected with 40 said weft-supply mechanism, of an electric circuit extending from the magnet to an automatic circuit-closing device attached to a spindle of a shuttle, and said automatic circuit-closing device being adapted to be opened or closed, respectively, by the presence or 45 absence of weft carried by said spindle, and the said spindle.

25. In a loom the combination with a shift-able, cellular shuttle-box, and a shuttle-magazine, of means for shifting said box in order 50 to take a fresh shuttle into its working cell and to bring the auxiliary cell into line with the race, and means for controlling the time of the operation thereof, said means comprising an electric circuit including a generator 55 and having a break which is closed by the entry of a shuttle into the shuttle-box, and the shuttles, each having in it an electric circuit which closes with the exterior circuit when the shuttle is in place in the shuttle-box, said shuttle also having in it a circuit-closing device, held open by the weft, and adapted to 60 be closed when said weft is nearly or wholly exhausted.

65 said shuttle having in it a spindle provided with a circuit-closing device situated so as to be within the weft carried by the spindle.

26. In a loom, the combination with a shift-able, cellular shuttle-box, and a shuttle-magazine, of means for shifting said box in order 70 to take a fresh shuttle into its working cell and to bring the auxiliary cell into line with the race, and means for controlling the time of the operation thereof, said means comprising an electric circuit including a generator, 75 a magnet, and a shuttle having in it a partial electric circuit, and having in it also a spindle provided with a hollow or recess, said hollow or recess containing an automatic circuit-closing device consisting of two terminals, 80 both contact-surfaces of which are situated wholly within said hollow or recess in the spindle.

27. In a loom, the combination with a shift-able, cellular shuttle-box, and a shuttle-magazine, of means for shifting said box in order 85 to take a fresh shuttle into its working cell and to bring the auxiliary cell into line with the race, means for controlling the time of the operation thereof, comprising an electrically-actuated device having its circuit extending through the shuttle and having a circuit maker and breaker attached to the spindle of the shuttle and so situated as to be within the weft carried by said spindle, and the said 90 spindle.

28. In a loom, the combination with a shift-able, cellular shuttle-box, and a shuttle-magazine, of means for shifting said box in order 95 to take a fresh shuttle into its working cell and to bring the auxiliary cell into line with the race, and means for controlling the time of the operation thereof, said means consisting of a generator and magnet, and an electric circuit extending from the magnet to an 100 automatic circuit-closing device attached to a spindle of a shuttle, said automatic circuit-closing device being adapted to be opened or closed, respectively, by the presence or 105 absence of weft carried by said spindle, and the 110 said spindle.

29. In a loom, the combination with a shift-able, cellular shuttle-box, and a shuttle-magazine, of means for shifting said box in order 115 to take a fresh shuttle into its working cell and to bring the auxiliary cell into line with the race, and means for controlling the time of the operation thereof, said means comprising an electric circuit including a generator 120 and having a break which is closed by the entry of a shuttle into the shuttle-box, and the shuttles, each having in it an electric circuit which closes with the exterior circuit when the shuttle is in place in the shuttle-box, said shuttle also having in it a circuit-closing device, held open by the weft, and adapted to 125 be closed when said weft is nearly or wholly exhausted.

30. In a loom, the combination with a shift-able, cellular shuttle-box, and a shuttle-magazine, of means for shifting said box in order 130 to take a fresh shuttle into its working cell and to bring the auxiliary cell into line with the race, and means for controlling the time

of the operation thereof, comprising an electrically-actuated device having its circuit extending through the shuttle, and also having a circuit maker and breaker attached to and carried with said shuttle.

31. In a loom, the combination with a shiftable, cellular shuttle-box, and a shuttle-magazine, of means for shifting said box in order to take a fresh shuttle into its working cell and to bring the auxiliary cell into line with the race, and means for controlling the time of the operation thereof, said means consisting of a generator and magnet, and an electric circuit extending from the magnet to an automatic circuit-closing device in a shuttle, and said automatic circuit-closing device being adapted to be opened or closed, respectively, by the presence or absence of weft carried by said shuttle.

32. In a loom, the combination with the vibrating lay and a magazine on the loom-frame, of a shifting, cellular shuttle-box on the lay, said box being open at the side next the magazine for facility in receiving and discharging shuttles, a swell carried by the lay and stationary with respect to the shuttle-box, said swell being so placed as to close the open front of the cell in said box which is aligned with the race, mechanism for shifting said shuttle-box, and electrical means controlling the times of operation of said mechanism, said means comprising an open electric circuit including a generator and electromagnet and having in it a break, the closure of which is controlled by the weft in the shuttle.

33. In a loom, the combination with an automatic weft-supplying mechanism, having means for supplying shuttles to the loom as required, of means for controlling the time of

operation of such supply mechanism, said means comprising an electrically-actuated device having its circuit extended through the shuttle and the weft or filling carrier therein, and a circuit maker and breaker operated by the filling or yarn of the weft-carrier, the circuit being also made and broken by the throw of the shuttle.

34. In a loom, the combination with an automatic weft-supplying mechanism, having means for supplying shuttles to the loom as required, of means for controlling the time of operation of said supplying mechanism, said means comprising a magnet connected with said supplying mechanism, and an electric circuit extending from said magnet and adapted to be opened or closed by the presence or absence of weft in the shuttle.

35. Weft-supply mechanism for looms, comprising mechanism for supplying shuttles, as required, to a loom, of an electric circuit and mechanism controlling said supply mechanism, said circuit including a generator and having terminals at the shuttle-box, and the shuttles, each having in it an electric circuit with terminals which contact with those on the shuttle-box when the shuttle is in place therein, said circuit in the shuttle having in it a break which is closed by the denudation of the weft from the weft-holder in the shuttle.

In witness whereof we have hereunto signed our names, this 18th day of April, 1899, in the presence of two subscribing witnesses.

WILLIAM H. BAKER.
FREDERIC E. KIP.
